DESIGN FOR A SUPPORT FOR SPECTACLES OR THE LIKE

Fred Allen Swartz, Harrisburg, Pa.

Application March 6, 1941, Serial No. 99,373

Term of patent 14 years

To all whom it may concern:

Be it known that I, Fred Allen Swartz, a citizen of the United States, residing in Harrisburg, county of Dauphin, and State of Pennsylvania, have invented a new, original, and ornamental Design for a Support for Spectacles or the like, of which the following is a specification, reference being had to the accompanying drawing, forming a part thereof.

The figure is a perspective view of a support for spectacles or the like, showing my new design.

I claim:

The ornamental design for a support for spectacles or the like, substantially as shown.

FRED ALLEN SWARTZ.
